UNITED STATES PATENT OFFICE.

CHARLES MILLER, OF LONG ISLAND CITY, NEW YORK.

PATTERN-DISPLAYING DEVICE.

Application filed December 18, 1926. Serial No 155,752.

This invention relates more particularly to a class of devices for displaying the patterns of certain materials, and has for its primary object to provide a device adapted 5 to be employed in the manufacture and sale of classes of articles, especially the footwear of persons, for enabling selections to be made from the materials for the uppers of women's slippers and low shoes, in order to determine 10 how the designs of the materials should be effectively positioned since such materials are produced in a large variety of colors and designs in leathers, skins, embroidered, embossed and stamped satins, silks and other 15 fabrics, and it happens that when faulty selections of the patterns and colors are made a loss is apt to be entailed from waste of the materials and cost of labor. The invention also contemplates its use for enabling the 20 selection of harmonizing color effects and designs for groups of footwear especially those of fanciful styles, and to allow correct selections to be made for producing footwear to match particular styles of costumes.

25 The invention consists broadly of a base plate having on one of its faces in bas-relief one or more portions each of a figure of a given object for receiving thereon a removable sheet of the material of which at least a 30 part of the object is to be made, in order to determine the most advantageous way of positioning the material with reference to the design of its pattern and coloring as it should appear in the object when made.

35 Adapted to be removably disposed on the base plate is a cover plate having a cut-out positioned for receiving the figure. This cut-out is of a shape conforming to the contour of the figure, and the cut-out is also of slightly 40 larger area than the contour of the figure so that the figure and the portion of the sheet imposed thereon will extend through the cut-out when the plates are closed together. The artistic effect of the material on the figure 45 may then be considered for determining its proper position in making the object.

A further object of the invention is to provide a pattern demonstrating device of a simple, efficient and durable construction 50 which may be made in appropriate sizes and shapes.

With these and other objects in view, the invention will be hereinafter more fully explained with reference to the accompanying 55 drawing forming a part of this specification in which similar characters of reference indi-

cate corresponding parts in all the views, and will then be pointed out in the claims at the end of the description.

In the drawing, Figure 1 is an elevation of 60 one form of the device embodying my invention, and which shows the cover plate swung to open position from the base plate thereof.

Fig. 2 is an enlarged top plan of the device with the base plate and cover plate closed 65 together, and which shows the manner of displaying a sheet of pattern material in conjunction therewith, and

Fig. 3 is an enlarged sectional view taken 70 on the line 3—3 of Fig. 2.

The device has a base plate 10 which may be of any appropriate shape and size, though the form of the base plate illustrated is substantially rectangular. On the upper face 75 of the base plate may be one or more spaced figures 11, 12 each of a given object, such as an article of merchandise and especially the figure of a shoe for a person. The figure 11 shows approximately one-half of the shoe lengthwise including the foot or toe portion 80 13, shank portion 14, heel portion 15 and heel 16. The figure 12 may be of a form showing a plan of the complete toe portion, as 17, of the shoe, and each of the figures is embossed or otherwise provided on the base plate so that the figures extend therefrom in 85 bas-relief, and each figure is preferably a fairly accurate model in shape and size of a portion of the particular style of shoe represented.

To one of the side edges of the base plate 10 is hinged, at 18, one of the side edges of a substantially rectangular cover plate 19 adapted to be swung to and upon the face of the base plate having the extending figures 90 11, 12, and the base plate and cover plate are of similar sizes. In a part of the cover plate 19 is a cut-out or opening 20 of an area somewhat larger than the contour of the embossed figure 11 of the base plate, and the cut-out 20 is of a shape corresponding to the contour of this figure of the base plate. The cut-out 20 is located in the cover plate 19 so that when the plates are closed together the edges of the cut-out will surround in closely spaced 100 relation the figure 11 of the base plate, and the cover plate is also of such a thickness that the figure will extend through its cut-out. In another part of the cover plate 19 is a second cut-out or opening 21 which is of an area slightly larger than the contour of the figure 12 of the base plate, and the cut-out 105 110

21 is of a shape similar to the contour of the embossed figure 12. The cut-out 21 is located in the cover plate for receiving the figure 12 of the base plate when both plates are closed together with the edge of the cut-out 21 surrounding in closely spaced relation the figure 12, and the figure 12 is embossed of a depth so that the figure extends through the cut-out 21.

10 Extending from the base plate 10 around the figure 11 is a rib 22 which is in spaced relation to the figure, and in the face of the cover plate 19 opposed to the figure 11 of the base plate is a groove 23 which surrounds the 15 cut-out 20 of the cover plate. The groove 23 is of greater width and depth than the width and height of the rib 22 of the base plate, and the rib and groove are in such related positions that the rib will be admitted 20 in the groove when the plates are closed. Also protruding from the base plate around the figure 12 is a rib 24 which is spaced from the figure, and in the face of the cover plate opposed to the figure 12 25 is a groove 25 which surrounds the cut-out 21. The groove 25 is of greater width and depth than the width and height of the rib 24 of the base plate, and the groove 25 is provided in a part of the cover plate for receiving the rib 24 when the plates are closed.

When the plates 10 and 19 are closed they may be releasably locked by means of a catch, as 26, which may be in the form of a 35 spring strip, as 27, having its lower end attached at 28 to the central part of the side edge of the base plate opposite to the hinges 18. The spring strip 27 extends upwardly above the edge of the cover plate 19, and 40 the upper end is bent to provide an angularly projecting head as 29 for removably engaging the upper face of the edge portion of the cover plate when closed upon the base plate, as shown. To unlock the plates the 45 head 29 is directed away from the edges of the plates, and the cover plate may then be swung to open position from the base-plate.

When it is desired to determine if the 50 pattern of a certain material is appropriate for making a portion of the object or article or shoe represented by the embossed figures of the base plate, or to determine how the 55 pattern of the material should be correctly positioned when used in making the object or shoe a sheet, as A, of the material which may be of fancy leather, skin, embroidered, embossed or stamped satin, silk or other material is spread over one or both of the 60 figures 11, 12 and over the ribs surrounding the figures of the base plate following the swinging of the cover plate 19 to open position from the base plate 10. The cover plate is then closed upon the material and 65 on the base plate, at which time the parts

of the material around each figure will be engaged by the rib adjacent to the figure and by the groove contiguous to the companion cut-out to the figure of the cover plate for causing the material to be stretched taut 70 upon the figure. The general effect of the material as it would appear in the shoe may then be studied, and by rearranging the material accordingly in the device the most advantageous way of using the material 75 may then be readily determined. Moreover, by the use of the device suitable selections may be made from various materials for producing shoes to match different styles 80 of women's costumes.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope 85 thereof.

Having thus described my invention, I claim as new and desire to secure by Letters Patent:—

1. A pattern displaying device, comprising a base plate having on one of its faces in bas-relief a portion of the figure of a given object for receiving thereon a removable sheet of the material of which at least a part of the object is to be made, a cover plate for being removably disposed on the base plate, said cover plate having a cut-out positioned for receiving the figure and the cut-out being of a shape conforming to the contour of the figure of the base plate, the cut-out also being of slightly larger area 95 than the contour of the figure whereby the figure and the portion of the sheet of material imposed thereon will extend through the cut out when the plates are closed together, and coacting means on the face of the base plate and the cover plate adjacent the figure and the cut-out for stretching and 100 removably holding the sheet of material taut on the figure.

2. A pattern displaying device, comprising 115 a base plate having on one of its faces in bas-relief a portion of the figure of a given object for receiving thereon a removable sheet of the material of which at least a part of the object is to be made, a cover plate hinged to the base plate for being swung upon and from the base plate, said cover plate having a cut-out positioned for receiving the figure and the cut-out being of a shape conforming to the contour of the figure of the base plate, the cut-out also being of slightly larger area than 120 the contour of the figure whereby the figure and the portion of the sheet of the material imposed thereon will extend through the cut-out when the plates are closed together, coact- 125 130

ing means on the face of the base plate and cover plate adjacent the figure and the cut-out for stretching and removably holding the sheet material taut on the figure, and means 5 for detachably fastening the cover plate when closed upon the base plate.

3. A pattern displaying device, comprising a base plate having on spaced parts of one of its faces in bas-relief portions of a plurality of figures each of a given object for receiving thereon a removable sheet of the material of which at least a part of the respective object is made, a cover plate for being removably disposed on the base plate, 10 said cover plate having spaced cut-outs positioned for receiving the figures of the base plate and each cut-out being of a shape conforming to the contour of each of the figures of the base plate, the cut-outs also being of 15 slightly larger areas than the contours of the figures whereby each figure and the portion of the sheet of the material imposed thereon will extend through the surrounding cut-out when the plates are closed together, said 20 cover plate having a groove surrounding each of its cut-outs and the face of the base plate having a protruding rib surrounding each of its figures, said ribs and the materials thereon being adapted to be seated in the grooves of 25 the cover plate for stretching and removably holding the sheet materials taut on the figures 30 with the closing of the plates.

4. A pattern displaying device, comprising a base plate having on spaced parts of one of its faces in bas-relief portions of a plurality of figures each of a given object for receiving thereon a removable sheet of the material of which at least a part of the respective object is made, a cover plate for being removably disposed on the base plate, 35 said cover plate having spaced cut-outs positioned for receiving the figures of the base plate and each cut-out being of a shape conforming to the contour of each of the figures of the base plate, the cut-outs also being of 40 slightly larger areas than the contours of the figures whereby each figure and the portion of the sheet of the material imposed thereon will extend through the surrounding 45 cut-outs when the plates are closed together, said cover plate having a groove surrounding each of its cut-outs, the face of said base plate having ribs surrounding 50 said bas-relief portions, said ribs and the materials thereon being adapted to be seated in the grooves of the cover plate for stretching and removably holding the sheet 55 materials taut on the figures with closing of the plates, and means for detachably fastening the cover plate when closed on the 60 base plate.

This specification signed this 17th day of December, A. D. 1926.

CHARLES MILLER.
